UNITED STATES PATENT OFFICE.

EARL C. GROVES, OF HOBSON, MONTANA, ASSIGNOR OF ONE-THIRD TO WAITE LAND AND LIVESTOCK COMPANY, OF UTICA, MONTANA, A CORPORATION OF MONTANA, AND ONE-THIRD TO J. E. LANE, OF LEWISTOWN, MONTANA.

ROTARY ENGINE.

Application filed May 25, 1921. Serial No. 472,440.

To all whom it may concern:

Be it known that I, EARL C. GROVES, a citizen of the United States, residing at Hobson, in the county of Fergus and State of Montana, have invented certain new and useful Improvements in Rotary Engines, of which the following is a specification, reference being had to the accompanying drawings.

10 This invention relates to certain improvements in rotary engines and has relation more particularly to a device of this general character wherein the motive force is a fluid under pressure such as air, steam, and
15 the like, and it is an object of the invention to provide a novel and improved device of this general character wherein the stator and rotor are provided with coacting abutments and wherein one of said abutments is movable to permit unhindered rotation of the rotor.

Another object of the invention is to provide a novel and improved device of this general character wherein a sliding piston 25 is carried by the rotor and normally urged outwardly into working position, together with coacting means carried by the rotor and stator to impart the requisite inward movement to said abutment at requisite intervals 30 to permit said rotor to have unobstructed or unhindered rotation.

It is also an object of the invention to provide a novel and improved engine of this general character wherein the induction and 35 eduction of the operating fluid is under control of the rotor, together with manually operated means for reversing the functioning of said openings so that the expansive fluid may be admitted at either side of an abutment.

40 The invention consists in the details of construction and in the combination and arrangement of the several parts of my improved engine whereby certain important 45 advantages are attained and the device rendered simpler, less expensive and otherwise more convenient and advantageous for use, as will be hereinafter more fully set forth.

The novel features of my invention will 50 hereinafter be definitely claimed.

In order that my invention may be the better understood, I will now proceed to de-

scribe the same with reference to the accompanying drawings, wherein:

Figure 1 is a vertical sectional view taken 55 through a motor constructed in accordance with an embodiment of my invention and substantially on the line A—A of Figure 1.

Figure 2 is a sectional view taken substantially on the line 2—2 of Figure 1. 60

Figure 3 is a fragmentary elevational view of the engine as herein embodied with a head of the stator removed, and

Figure 4 is a fragmentary detail view partly in section and partly in elevation, the 65 line of section being substantially on the line 4—4 of Figure 1.

As disclosed in the accompanying drawings, S denotes a stator substantially cylindrical in form and which has disposed axially thereof the shaft 1. Arranged within the stator S is the rotor R including a hub 2 fixed to the shaft 1 and radiating from opposite end portions of the hub 2 are the spokes or arms 3 connected to and supporting the drum or cylinder 4. The opposite end portions of the cylinder or drum 4 snugly fit within the opposite end portions of the rotor R and the central portion of the stator S is outwardly off-set to provide an 70 annular chamber 5. The wall of the drum or cylinder 4 is provided with a longitudinally disposed slot 6 through which is slidably directed a radially movable sliding piston 7 which normally projects beyond the 75 periphery of the cylinder or drum 4 and snugly engages within the chamber 5. The central portion of the piston 7 is provided with an inwardly disposed radial arm 8 which is also freely disposed through an 80 arm 9 connecting a pair of adjacent spokes 3. Interposed between the spoke 3 and the piston 7 is a coil spring 10 encircling the arm 8 and which serves to constantly urge the piston 7 outwardly to maintain the same 85 in requisite working position within the chamber 5.

The opposite end portions of the piston 7 are provided with the outstanding extensions or arms 11 and rotatably mounted upon the outer extremity of each of said arms or extensions 11 is a roller 12 which is adapted to engage a cam member 14 suitably secured to an inner face of the stator S. The flange

14 is so positioned that at proper intervals, the piston 7 will be caused to swing inwardly so that the stationary abutment 15 carried by the stator S will offer no obstruction or hindrance to the requisite rotation of the rotor. The stationary abutment 15 has close contact with the periphery of the rotor R and extends entirely across the chamber 5 and the working face of the abutment 15 is provided with the packing 16 which has direct contact with the periphery of the rotor R.

The bore of the stator S, at opposite sides of the stationary abutment 15, is provided with the ports 17 in communication with the chamber 5. The outer end portion of each of said ports 17 are in communication with the ports *a* and *b*, the port *a* constituting an exhaust port and the port *b* leading to a chest 18. At the junctions of each of the ports 17, *a* and *b* is a hollow rotary valve 19 provided with the ports *c* and *d* which are adapted to register either with the ports 17 and port *a* or port 17 and port *b* so that in practice, each of the ports 17 may constitute either an inlet port or exhaust port in accordance with the direction of travel of the rotor R.

Each of the valves 19 is engaged with its spindle 20 and to an extended portion of the spindle 20 is loosely fixed an arm 21. The arm 21 of one spindle is substantially in parallelism with the arm of the second spindle and the outer or free end portions of said arms 21 are pivotally engaged with the elongated lever 22, provided at one end with a hand grasp 23 whereby the lever 22 may be manually operated to swing the arms 21 to move the valves 19 into reverse position as required.

Fixed to the outer end of each of the spindles 20 is a disc 19^a and connecting the disc 19^a and the adjacent arm 21 is a retractile member or spring 24 which operates to normally maintain the arm 21 in contact with a stop 25 carried by the disc 19^a yet at the same time permits the valve to have the requisite rocking movement.

Each of the valves 19 is provided with a radially disposed and outstanding elongated arm 26, the arm of one valve being substantially perpendicularly related to the arm of the second valve. When the arm 26 of one of the valves 19 is disposed in a direction toward the second valve, said first named valve has its ports *c* and *d* positioned to control the inlet of the expansive fluid into the chamber 5 from the chest 18 and the second valve has its ports *c* and *d* in communication with the second port 17 and the adjacent port *b* so that said second port 17 is open for the purpose of exhaust.

In communication with the chest 18 is a pipe 27 leading from a suitable source of fluid under pressure such as steam, air, or

the like, and the flow of said fluid into the chest 18 is under control of a rotary valve V and the movement of the valve V is preferably under the influence of a governor so that the rotor may be caused to revolve at a constant rate of speed.

The valve V has secured to an extended portion of its stem a rock arm 28 to which is operatively engaged a rod 29, also operatively engaged with an end portion of a bell crank lever 30 pivotally supported at its heel portion by a wall of the stator S. The opposite end portion of the bell crank lever 30 is operatively engaged with a rod 31 which extends inwardly of the stator S and which is provided at its inserted end with a roller 32 constantly in contact with a tapered or cam cover 33 fixed to the shaft 1 for rotation therewith but capable of movement longitudinally thereof under the influence of a governor, not shown. As the collar or cam 33 moves outwardly upon increased speed of the shaft, the valve V will be correspondingly rotated to reduce the admission of the expansive fluid, and vice versa. The roller 32 is constantly held into contact with the collar or cam 33 and the valve V normally maintained in full open position by the retractile spring 34 secured to an arm of the bell crank lever 31 and the adjacent wall of the stator S.

In practice, the cam members 14 coact with the rollers 12 to retract the sliding piston 7 when the same closely approaches the stationary abutment 15 and the spring 10 automatically returns said piston in working position after the stationary abutment has been passed. The sleeve or cylinder 4 at one end portion is provided with the inwardly disposed cam flange 35 which coacts with a roller 36 carried by the inner end portion of a rod 37 slidably disposed through the adjacent wall of the stator S. The outer end portion of the rod 37 is provided with a head or enlargement 38 which normally overlies the free or outer end portion of the arm 26 carried by the valve coacting with the port 17 serving as the inlet. As the cam or flange 35 passes over the roller 36, the rod 37 is forced inwardly whereby the head 38 engages the arm 26 and moves the valve into closed position and particularly during the period the piston 7 is passing the stationary abutment 15.

From the foregoing description, it is thought to be obvious that an engine constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to

the precise arrangement and formation of the several parts herein shown in carrying out my invention in practice except as hereinafter claimed.

5 I claim:—

In a rotary engine embodying a casing having a stationary abutment and a rotor having a sliding piston, ports in the casing communicating with the interior of the casing on either side of the stationary abutment with a common expansive fluid inlet and with the atmosphere, a valve in each of said ports movable to connect the interior of the casing with the expansive fluid inlet 15 or with the atmosphere, said valves being

reversely disposed, means for simultaneously shifting said valves to reverse the port connections thereof, a member intermittently reciprocated during the operation of the engine, and an operating arm for each of said valves and lying in the path of said member when its associated valve is in position to connect the interior of the casing with the expansive fluid inlet, the member contacting with an arm to oscillate the second 25 valve independently of the reversing means.

In testimony whereof I hereunto affix my signature.

EARL C. GROVES.
